APPARATUS FOR HANDLING CONCRETE
BLOCKS

Robert M. Gray, Sheffield, Ala.

Application April 10, 1944, Serial No. 530,339

13 Claims. (Cl. 214—18)

1

This invention relates to apparatus for handling and curing molded concrete products, particularly concrete building blocks as they come, freshly molded, from the block making machine, and has for its principal object the provision of apparatus of the character designated which shall be effective to reduce breakage to a minimum and eliminate the necessity of manual handling of the blocks until set and cured.

A further object of my invention is to provide apparatus for loading concrete blocks on racks in multiple layers as they come from the block making machine, together with a continuous kiln for the racks, means for conveying the racks through the kiln, and means for unloading the racks after they have passed through the kiln and for returning them to their initial station for re-loading.

A further object of my invention is to provide, in association with a concrete block making machine, a continuous circular kiln for curing the concrete blocks, a rotary support in the kiln, a multiplicity of racks for the blocks adapted to be carried around the kiln on the support, and mechanism operative responsive to movement of the blocks from the block making machine for loading and unloading the racks and for operating the rotary conveyor.

A still further object of my invention is to provide, in apparatus of the above mentioned character, racks each having a plurality of superposed shelves, and in which the shelves are loaded and unloaded, one at a time, by the mechanism responsive initially to movement of blocks from the block making machine.

In the art to which my invention relates, concrete blocks are molded by a machine, and as molded are placed automatically on pallets and delivered from the machine. It has heretofore been the practice to remove these pallets one at a time as they come from the machine, by means of an air hoist and place the pallets on racks having wheels thereon which are pushed by hand into a kiln and cured. When the blocks are cured, the racks are removed from the kiln, and are unloaded by another hoist, and the pallets returned to the block making machine. It is well known that freshly made concrete blocks are relatively fragile and that in the handling of the blocks in the manner described, pallets are sometimes dropped, rough places over which the racks may

be moved cause them to be jostled and jarred, and carelessness of workmen all combine to produce a high percentage of breakage. In the practical operation of a block making plant, I have experienced a loss due to breakage as high as twenty five percent. Besides the loss due to breakage, the labor cost of handling the blocks in the manner described is excessive. It is accordingly the principal object of my invention to provide a machine for handling the blocks as they come from the block making machine which will load the pallets on the racks, propel the racks through a circular kiln and unload them as they complete their circuit of the kiln, without any manual handling of the blocks or the racks.

In the accompanying drawings forming a part of this application,

Fig. 1 is a plan view showing the general arrangement of a circular kiln having my improved block handling mechanism associated therewith;

Fig. 2 is a fragmentary sectional plan view of the kiln drawn to an enlarged scale, showing the places of loading and unloading the racks and showing somewhat diagrammatically the machines associated therewith;

Fig. 3 is a side elevation of a unit adapted for loading a rack and showing the rack loaded and in raised position;

Fig. 4 is a sectional view taken along the line IV—IV of Fig. 3;

Fig. 5 is a sectional plan view taken along the line V—V of Fig. 4;

Fig. 6 is a side elevation, drawn to an enlarged scale, with parts broken away, showing details of the conveyors embodied in the loading and unloading machines;

Fig. 7 is a fragmentary plan view showing details of the conveyors and with the shuttle conveyor beginning its return travel after loading or unloading a rack;

Fig. 8 is a detail view showing mechanism for moving the circular support on which the racks are carried through the kiln, and showing the plunger of the hydraulic cylinder in retracted position;

Fig. 9 is a wiring diagram of the controls for the motor operating the conveyors of the loading machine;

Fig. 10 is a side elevation of the loading machine showing the rack in its lowest position at

the beginning of the loading operation, together with a diagrammatic showing of the hydraulic controls for operating the apparatus;

Fig. 11 is a wiring diagram of the controls for the magnetic valves employed with the hydraulic cylinders in the loading operation;

Fig. 12 is a vertical sectional view of a typical three-way magnetic valve for controlling a hydraulic cylinder in accordance with my invention;

Fig. 13 is a sectional view of the valve shown in Fig. 12 taken at right angles to the showing in Fig. 12;

Fig. 14 is a sectional view of a typical one-way valve associated with the hydraulic cylinders;

Fig. 15 is a view similar to Fig. 8 showing the mechanism for imparting intermittent motion to the circular support on which the racks are carried in the kiln and showing the plunger in extended position;

Fig. 16 is a view similar to Fig. 10 showing the unloading machine with the rack in its highest position at the beginning of the unloading operation, together with the hydraulic controls for operating the apparatus; and

Fig. 17 is a wiring diagram of the controls for the magnetic valves and motor employed with the hydraulic cylinders in the unloading operation.

Referring to the drawings, I show diagrammatically in Figs. 1 and 2 a block making machine 10 which may be of any well known design adapted to mold concrete blocks and deliver them from the machine on pallets P. A chain type conveyor 12 is included in the block making machine for conveying the pallets out of the machine. At 13 I show a circular kiln for curing the blocks and disposed within the kiln is a circular rotary support 14 comprised of concentric rails 16 and 17 joined together by suitable cross members 18. The rails 16 and 17 rest on rollers 19 and 21 (Fig. 3) which are suitably journaled at the sides beneath the rails so that the track may be rotated on the rollers within the kiln. Supported by the cross members 18 are a plurality of racks 22 each constructed from vertical frame members 23 and 24 joined along the side by lateral frame members 26 forming a plurality of superposed shelves 27 upon which the loaded pallets P are adapted to rest and be carried through the kiln by rotation of the rotary support 14. It is contemplated that the kiln shall be of such dimensions that the racks 22 may be loaded one at a time as the pallets are delivered from the block making machine 10, and that by the time a rack has completed its rotation around the circular kiln and arrived back at its starting position, the blocks will be completely cured and ready for use. As each rack is loaded and placed on the rotary support 14, motion is imparted to the support by means of a hydraulic cylinder 28 which is adapted, in a manner to be described later, to move the support the width of one rack at a time.

The kiln 13 is provided with an opening 29 through which the racks 22 are loaded and unloaded, and disposed between the block making machine 10 and the opening is my improved loading machine 31 which is adapted to load the racks 22 in response to the delivery of loaded pallets P from the block making machine 10, and to place the racks on the rotary support 14. A similar machine 32 is disposed in front of the opening 29 to unload the racks one at a time after they have passed around the kiln, and to deliver the pallets to a roller conveyor 33 driven by any suit-

able means, not shown, where the blocks are removed by means of a suitable air hoist 34 and crane 36.

The loading and unloading machines 31 and 32 are identical in construction, but operate in a reverse order. A description of the construction of one of the machines will accordingly serve for both except for the operating controls thereof. The loading machine 31, shown in Figs. 3 to 7 inclusive, comprises a frame having outer vertical members 37 on one side and 38 on the other side which are joined together at the rear by a transverse channel 39 and at the front by a transverse channel 41. There are also inner vertical frame members 42 and 43 (see Figs. 4, 5 and 7) which are joined to the transverse members and to the outer vertical frame members by diagonal braces 44 and 46. Supported on the inner vertical members 42 and 43 are stationary conveyor frame members 47 and 48. Mounted between the vertical members 37 and 42 at both front and rear are stub shafts 49 and 51 having smooth disks 52 and 53 mounted on their inner ends. Mounted between the vertical members 38 and 43 at both front and rear are stub shafts 54 and 56 which also have smooth disks 57 and 58 mounted on their inner ends. Conveyor chains 55 and 60 are passed over the disks 52 and 53 and 57 and 58 to form means for supporting and moving the pallets P from the concrete block making machine.

Disposed between the side frame members 47 and 48 of the stationary conveyor is a movable, or shuttle conveyor comprised of side members 59 and 61 braced by diagonal struts 45 and having shafts 62 and 63 mounted in plates 64 and 66 secured to the side frame members at the rear end, and in plates 67 and 68 secured to the side frame members 59 and 61 at the forward ends thereof. Mounted on the ends of the shafts 62 and 63 are smooth disks 69 and 71 respectively over which conveyor chains 72 and 73 run. The shuttle conveyor is supported by means of diagonal channels 74 and 76 which are secured to the side frame members 59 and 61 and which extends downwardly. See Figs. 3 and 4. Mounted across the channels 74 and 76 are shaft 77 and 78, the upper shaft 77 having flanged rollers 79 and 81 thereon and the lower shaft 78 having similar rollers 82 and 83 thereon. The wheels 79 and 81 bear respectively on the upper surfaces of I beams 84 and 86 and the wheels 82 and 83 bear respectively against the lower surface of said I beams so that the movable conveyor can be reciprocated. The I beams 84 and 86 are secured to the inner vertical frame members 42 and 43 and to the transverse members 39 and 41. As may be seen from a consideration of Figs. 3 to 7 inclusive, the shuttle conveyor can be moved rearwardly to assume a position between the side members 47 and 48 of the stationary conveyor.

Referring particularly to Fig. 4, both the stationary and the shuttle conveyors are driven in unison from a motor 87 suitably supported on top of the stationary conveyor frame. Embodied in the casing of the motor is a magnetic brake 88 which is released when energized but which prevents rotation of the motor when de-energized. The motor 87 drives the conveyors through a reduction gear assembly 89 and a drive shaft 91, connected by a sprocket and chain 92 with a sprocket 93, mounted on a shaft 94, extending across the frame and supported in suitable bearings 96 and 97, mounted in the vertical members 37 and 38. Mounted on the shaft

94 are sprockets 98 and 99, which are connected by means of chains 101 and 102 to sprockets 103 and 104, which are mounted on stub shafts 106 and 107. The shafts 106 and 107 are mounted on opposite sides of the conveyors in suitable bearings 108, 109, 111 and 112, respectively, on the vertical frame members 37 and 42 and 38 and 43. Near the inner end of the shaft 106 is a toothed sprocket 113 adapted to mesh with the links of the sprocket chain 55 of the stationary conveyor and a toothed sprocket 114 adapted to mesh with the links of the sprocket chain 72 of the shuttle conveyor. Near the inner end of the shaft 107 is a toothed sprocket 115 adapted to mesh with the links of the sprocket chain 68 of the stationary conveyor. On the extreme inner end of the shaft 107 is a toothed sprocket 117 adapted to mesh with the links of sprocket chain 73. The chains of both the stationary and the shuttle conveyor are thus driven in unison from the motor 87 and the conveyor chains are free to slip, if necessary, on the smooth disks over which they run.

The shuttle conveyor is reciprocated by means of a hydraulic cylinder 118 suitably supported between the frame members of the stationary conveyor and having its plunger 119 connected to the forward end of the shuttle conveyor at 121. The wheels 78, 81, 82 and 83 being mounted to bear against the upper and lower surfaces of the I beams 84 and 86, permits the extension and retraction of the shuttle conveyor.

When the shuttle conveyor is in its extended position, as shown in Figs. 3 and 5, it is in position to load the pallets P with their concrete blocks on to the rack 22. Mounted in the opening 29, in front of the loading machine 31 is a hydraulic hoist comprising a cylinder 122 and plunger 123. A plunger head 124 is provided at its sides with supporting members 126 and 127 which are adapted to straddle the side frame members 59 and 61 of the shuttle conveyor to engage and support the racks 22 with considerable clearance between the head 124 and the side frame members. As shown in Fig. 3, the rack 22 is in its highest position with all of the shelves 27 loaded. At the beginning of the loading operation, the rack is in position shown in Fig. 10 to load the uppermost shelf. As each shelf is loaded the rack is raised by the hoist to permit loading of the next lower shelf. After the lowest shelf is loaded, the shuttle conveyor is retracted and the rack is lowered by the hoist to rest on the rotary support 14 and be carried around the kiln 13.

The operation of my improved block handling apparatus is controlled by means of a system of magnetically operated hydraulic valves and electrical switches and relays which will now be described. The rotary support operating cylinder 28 has a suitable hydraulic fluid admitted alternately to opposite ends thereof by means of magnetically operated 3-way valves 3V2 and 3V3 connected by conduits 128 and 129 to opposite ends of the cylinder. The hydraulic cylinder 118 which actuates the shuttle conveyor on the loading machine 31 has a suitable fluid admitted alternately to opposite ends thereof by means of magnetically operated 3-way valves 3V1 and 3V4 through conduits 131 and 132. See Fig. 10. Similar valves 3V5 and 3V6 admit fluid alternately to the hydraulic cylinder 118 operating the shuttle conveyor on the unloading machine 32. See Fig. 16. The hoisting cylinder 22 has its plunger 123 raised by fluid under pressure

and is lowered by gravity. Fluid is admitted to the lower end of the cylinder 122 of the loading machine 31 by means of a magnetically operated valve 1V1 through conduit 120 and is exhausted therefrom by means of a branch conduit 125 and a magnetically operated valve 1V2. The cylinder 22 of the unloading machine 32 has fluid admitted thereto from a corresponding magnetic valve 1V4 through conduit 130 and exhausted therefrom through a magnetically operated valve 1V3 and branch conduit 135. See Fig. 16.

Examples of the construction of suitable magnetically operated valves are shown in Figs. 12, 13 and 14. The 3-way valves, such as may be employed for operating the track cylinder 28 and the shuttle conveyor cylinder 118 are shown in Figs. 12 and 13. Each comprises a housing 133 to which fluid is admitted under pressure through a conduit connection 134. Two spring 15 pressed valves 136 and 137 are located within the housing and control the flow of fluid through outlets 138 and 139. The outlet 139 has connected thereto a conduit leading to its associated hydraulic cylinder such as 128 and 129, while the outlet 138 leads to the exhaust. Mounted in the housing 133 is a lever 141 pivoted at 142. The stems of the valves 136 and 137 bear in notches 143 and 144 in the upper and lower surfaces respectively of the lever 141. The opposite end of the lever 141 is connected to the lower end of a core 146 of a solenoid 147 mounted on the casing 133. When the solenoid 147 is energized, the lever 141 is raised, opening the valve 136 and closing the valve 137 so that fluid under 20 pressure is admitted through the valve 136 to pass outwardly through the connection 139 to the cylinder with which the valve is connected. When the solenoid is de-energized, the core 146 returns to its normal down position shown in 25 Fig. 12, in which valve 137 is opened and valve 136 closed. In this position, fluid passes from the cylinder through the connection 139 and valve 137 to the exhaust 138. The valve shown 30 in Fig. 14 is an example of a suitable valve which may be employed with the cylinder 122 and comprises a valve housing 148 having located therein a single valve 149 which is connected to the lower end of a core 151 of a solenoid 152 mounted on the casing. When the solenoid 152 is energized 35 the valve 149 is opened. When the solenoid is de-energized, the valve moves to its down or closed position, shown in Fig. 14.

The electrical controls for the loading machine 31 will now be described having reference particularly to Figs. 8, 9, 10 and 11. The source of electrical energy is shown at L1, L2 and L3. A switch LS1 (see Fig. 6) is located on the stationary conveyor in position to be engaged and closed by the pallets P being delivered from the conveyor 12 40 of the concrete block making machine. As each pallet closes the switch LS1, it completes a circuit through relay CR1 which energizes a magnetic coil 153, which in turn closes switch LC to the motor 87. The motor 87 starts the stationary and shuttle conveyors in operation as hereinbefore described to advance the first pallet, indicated in Fig. 9 as P1. The relay CR1 may have a member 150 associated therewith to delay immediate re-opening of the circuit as soon as the pallet passes over the switch LS1. This provides a slight time interval between the opening of the motor circuit when the brake 88 stops the motor 87 and the conveyors. The operation described is repeated until five pallets have been 45 delivered from the block making machine. When

the fifth pallet is delivered, pallet P1 will have assumed a position to close a switch LS2 located alongside the stationary conveyor. This switch completes a circuit from L1 through relay CR2 which in turn completes the circuit through the magnetic coil 153, closing motor switch LC and again starts the motor 87. Associated with the relay CR2 is a member 154 which is adapted to hold the relay closed and maintain the motor 87 in operation until all five of the pallets have been delivered to the outer end of the shuttle conveyor.

At the outer end of the shuttle conveyor is a switch LS3 in position to be engaged and closed by the first pallet, P1, arriving at the outer end of the shuttle conveyor. When the switch LS3 is closed, it completes a circuit through a relay CR3 which in turn controls a magnetic coil 156 which is adapted to operate a switch LS4 which completes a circuit through the magnetically operated valve IV1 and admits fluid under pressure to the lower end of the cylinder 122. Carried by the plunger head 124 is a downwardly extending arm 157 having notches 158 therein at intervals corresponding to the distance between the shelves 27 of the rack 22 and the distance necessary to raise the rack at the beginning and ending of the loading operation to clear the shuttle conveyor. A stem 159 of the switch LS4 is adapted to be engaged in one of the notches 158 when the switch LS4 is open. A spring 161 moves the switch towards opening position when the coil 156 is de-energized. Thus, the closing of the switch LS4 by energizing the coil 156 causes the plunger 123 of the cylinder 122 to be raised, raising the rack 22. As the rack is raised, the switch LS3 opens by disengagement of the pallet P1 therewith, but the switch LS4 remains closed due to the fact that the stem 159 is out of a notch 158 and is sliding on the arm 157. The switch LS4 will thus remain closed until the next notch 158 is reached when the spring 161 will force the stem 159 into the notch and open the switch.

The operation described is repeated until all of the shelves 27 of the rack 22 have been loaded. It will be noted that the lowest notches 158 on the arm 157 are relatively close together so that the rack 22 is raised only sufficient distance in its last upward movement to clear the pallets off the shuttle conveyor. As the arm 157 approaches its last upward movement a trip 162 on the side thereof opposite the notches 158, engages and closes the switch LS5 which completes the circuit through magnetic valve 3V1 (see Fig. 11) admitting fluid under pressure to the forward end of hydraulic cylinder 118 which causes the plunger 119 to move inwardly telescoping the shuttle conveyor back into the stationary conveyor and clear of the rack 22.

As the shuttle conveyor reaches its most rearward position, it engages and closes a switch LS6 which completes a circuit through a double throw switch LS7 to the magnetically operated valve IV2 which opens and allows the hoist with its loaded pallets to be lowered by gravity on to the rotary support 14 to the position shown in Fig. 10. The plunger head 124 continues to move downwardly until it is clear of the rack so that the rotary support may be turned. As the hoist moves to its lowest position the head 124 engages and moves double throw switch LS7 to its lowest position to complete the circuit to magnetic valve 3V2 admitting fluid under pressure to the cylinder 28 to impart rotary motion to the rotary support 14. The cylinder 28 has a plunger 162 with a

pivoted head 163 thereon adapted to engage a cross member 18 and impart movement to the rotary support during outward movement of the plunger, but to pivot out of the way to the dotted position of Fig. 8 as the plunger 162 is retracted. In order that the rotary support may be accurately positioned each time it is advanced, I connect to the side of the cylinder 28 a conduit 164 which is spaced from the end of the cylinder a distance slightly greater than the width of one of the cross members 18 on the rotary support. The conduit 164 leads to a cylinder 166 having a plunger 167 therein adapted to engage a cross member 18 on the rotary support 14 but which is normally pushed downwards out of the way by means of a spring 168. When fluid is admitted to the cylinder 28 to force the plunger 162 outwardly, the leading cross member 18 is first moved over the plunger 167. When the plunger 162 has advanced an amount sufficient for fluid to be admitted to the conduit 164 and cylinder 166, the plunger 167 is forced outwardly to engage the next succeeding cross member 18 and thus position the rotary support 14 accurately so that the succeeding rack 22 is properly positioned over the hoist members 126 and 127.

When the plunger 162 reaches its outermost position, it engages and closes switch LS8 which in turn completes a circuit energizing relay CR5, which completes a circuit through magnetic valve 3V3 admitting fluid to the opposite end of cylinder 28 to return the plunger 162 to its inner position. The relay CR5 also closes a circuit to magnetic valve IV1 through switch LS4, admitting fluid under pressure to the lower end of cylinder 122 and raising the hoist the distance between the first two notches 158 on the arm 157. When the stem 159 drops into the second notch 158, switch LS4 is opened, stopping the hoist in position for the upper shelf 27 of the rack 22 to be loaded by the shuttle conveyor.

As the hoist and rack are raised the distance just described, a trip 168 on the member 127 engages and closes the switch LS9 which completes a circuit to magnetic valve 3V4 admitting fluid under pressure to the rear end of hydraulic cylinder 118 thus moving the shuttle conveyor to its outermost position in the rack 22 to again begin loading the rack.

When the rotary support 14 has been moved one step by the plunger 162 as previously described, closing switch LS8, it energizes magnetic relay CR5 and completes a circuit through magnetic valve IV4, admitting fluid under pressure to the lower end of cylinder 122 of the hoist for the unloading machine 32. See Figs. 16 and 17. This raises the hoist and loaded rack 22 a distance sufficient to bring the lower shelf 27 to a position slightly above the level of the shuttle conveyor. The relay CR5 also completes a circuit leading to magnetic valve 3V3, causing the plunger 162 to return into the cylinder 28, as already described. The relay CR5 is of the delayed action type and is provided with a member 165 to hold the circuits described closed a sufficient time for the plunger to be returned and for the hoist and loaded rack to be raised the required distance. The hoist employed with the unloading machine is provided with a depending arm 169 secured to the head 124, and has a trip 171 near the lower end. The trip 171 when the hoist is raised to the position just described, engages and closes a switch LS10 which completes a circuit to the magnetic valve 3V6, admitting fluid under pressure to the rear end of the cylinder

118, to move the shuttle conveyor outward in position to unload the rack 22.

As the shuttle conveyor nears its outermost position, switch LS11 carried thereby engages a trip on plunger head 124 and is closed, energizing magnetic relays CR6 and CR1 which control switch LS14, closing it and completing a circuit through magnetic valve 1V3, which exhausts fluid from the hydraulic cylinder 122, allowing the hoist to settle and the shuttle conveyor to assume the load of the first row of loaded pallets on the lower shelf 27 of the rack 22. The switch LS14 is similar to switch LS4, already described, and the arm 169 carried by the head 124 of the hoist is provided with notches 172 in which the stem 159 of the switch LS14 is adapted to drop and open the switch at the required intervals of lowering the hoist with the loaded rack 22.

When the pallets are lifted from the first shelves by the shuttle conveyor when lowering the hoist, switch LS12, carried by the shuttle conveyor is engaged and closed by one of the pallets completing a circuit through magnetic relay CR8 which in turn energizes magnetic coil 173 closing the controlling switch to motor 174, which starts the motor and the conveyors to carry the pallets with their blocks out of the rack 22 and deliver them to the roller conveyor 33. It will be seen by a comparison of Figs. 10 and 16 that the motor 174 must run in a direction opposite to motor 31. The blocks are then removed from the pallets by the hoist 34 and the pallets are returned by the roller conveyor to the block making machine 10.

As the pallets travel over the stationary conveyor they engage and close switch LS13, mounted on the stationary conveyor frame, which energizes relays CR8 and CR1, completing the circuit through the magnetic coil 158 and switch LS14 to magnetic valve 1V3, again exhausting fluid from the cylinder 122 and allowing the hoist to lower the rack 22 until the stem 159 of switch LS14 again engages in a notch 172. This positions the rack 22 so that the cycle of operations already described is repeated and the next shelf of pallets is unloaded.

When the hoist is lowered at the unloading of the last, or uppermost shelf 27, a trip 116 on the head 124 engages and closes a switch LS15 completing a circuit to magnetic valve 3V5 which admits fluid to the forward end of hydraulic cylinder 118, thus causing its plunger 119 to be retracted, together with the shuttle conveyor, returning the latter to its original position first described.

It will be understood that, in starting an operation as hereinbefore described, the switch LS3 at the end of the shuttle conveyor on the loading machine 31 should be closed manually to raise the hoist and rack 22 to a position to begin loading the rack and also switch LS9 should be closed to energize magnetic valve 3V4 and cause the shuttle conveyor to be moved to its extended position. It will also be necessary, of course, to hold the unloading machine 32 and its associated hoist out of operation until the first loaded rack 22 has made a complete circuit of the kiln and has returned to the opening 29 in position in front of the unloading machine 52.

From the foregoing it will be apparent that I have devised an improved block handling machine which is adapted to load the freshly molded blocks on racks, carry them around the circular kiln and unload them automatically as they are delivered on pallets from the block making ma-

chine. The pallets being lowered on to the racks and the racks on to the support by means of the hydraulic hoist insures that they will be handled gently and no blocks broken in loading. Further, the carrying of the racks around the kiln on the rotary support eliminates all danger of jostling and jarring the racks and the breaking of blocks for that reason. It will also be apparent that I have eliminated the necessity of manual handling of the blocks or the racks from the time the blocks are freshly made until unloaded from the racks.

I wish it to be understood that I do not desire to be limited to the exact details of construction shown and described, for obvious modifications will occur to a person skilled in the art.

What I claim is:

1. In apparatus of the character described, a machine for handling pallets bearing concrete blocks comprising a stationary conveyor, a shuttle conveyor adapted to telescope within the stationary conveyor and to be extended beyond the stationary conveyor, a stationary conveyor frame, a supporting track for the shuttle conveyor mounted on the stationary conveyor frame, means included in the stationary conveyor for delivering pallets to the shuttle conveyor when extended, a rack having a plurality of superposed lateral shelves on which the pallets are loaded, a hydraulic hoist for the rack, control means for the hoist operative responsive to the delivery of pallets to the shuttle conveyor and adapted to position the successive shelves beneath the shuttle conveyor and to raise the rack for the shelves to engage the pallets and lift them off the conveyor, and other control means operative responsive to raising the hoist to its highest position to retract the shuttle conveyor from the rack and lower the hoist and the rack.
2. In apparatus of the character described, a machine for handling pallets bearing concrete blocks comprising a stationary conveyor, a shuttle conveyor adapted to telescope within the stationary conveyor and to be extended beyond the stationary conveyor, a stationary conveyor frame, a supporting track for the shuttle conveyor mounted on the stationary conveyor frame, means included in the stationary conveyor for delivering pallets to the shuttle conveyor when extended, a rack having a plurality of superposed lateral shelves on which the pallets are loaded, a hydraulic hoist for the rack, control means for the hoist operative responsive to the delivery of pallets to the shuttle conveyor and adapted to position the successive shelves beneath the shuttle conveyor and to raise the rack for the shelves to engage the pallets and lift them off the conveyor, other control means operative responsive to raising the hoist to its highest position to retract the shuttle conveyor from the rack and lower the hoist and rack, a rotary support disposed to receive the rack as it is lowered by the hoist, a hydraulic cylinder and plunger for imparting intermittent rotary motion to the support, and control means for the hydraulic cylinder operative responsive to lowering the hoist to its lowest position.
3. In apparatus of the character described a machine for handling pallets bearing concrete blocks comprising a stationary conveyor including movable elements adapted to support and move the blocks, a shuttle conveyor adapted to telescope within the stationary conveyor and to be extended beyond the stationary conveyor, a supporting track for the shuttle conveyor dis-

posed beneath the stationary conveyor, a rack having a plurality of superposed lateral shelves on which the pallets are loaded, a hydraulic hoist for the rack, control means for the hoist operative responsive to the delivery of pallets to the shuttle conveyor and adapted to position the successive shelves beneath the shuttle conveyor and to raise the rack for the shelves to engage the pallets and lift them off the conveyor, other control means operative responsive to raising the hoist to its highest position to retract the shuttle conveyor from the rack and lower the hoist and the rack, a rotary support disposed to receive the rack as it is lowered by the hoist, a hydraulic cylinder and plunger for imparting intermittent rotary motion to the support, control means for the hydraulic cylinder operative responsive to lowering the hoist to its lowest position, and stop means to limit the motion imparted to the rotary support.

4. In apparatus of the character described, a machine for handling pallets bearing concrete blocks comprising a rack for receiving the pallets, a stationary conveyor having movable elements for moving the pallets, a shuttle conveyor adapted to telescope in the stationary conveyor and to extend outwardly therefrom and having movable elements adapted to deliver pallets onto the rack, and means operative responsive to complete loading of the rack to move the shuttle conveyor relative to the stationary conveyor.

5. In apparatus of the character described, a machine for handling concrete blocks comprising a stationary conveyor for the blocks, a rotary support, a multiplicity of racks for the blocks adapted to be carried by the support, mechanism for receiving the blocks from the stationary conveyor and for loading the racks, mechanism operative responsive to complete loading of each rack for lowering the rack onto the support, mechanism operative responsive to lowering the rack for imparting rotary motion to the support, and other mechanism for unloading the racks after they have passed around the support.

6. Apparatus for conveying and handling molded products comprising a circular movable support, a plurality of racks adapted to rest on the support and be carried thereby, mechanism for loading the molded products on the racks, mechanism for lowering the racks onto the support as they are completely loaded, other mechanism for unloading the products from the racks after they have passed around the support, control means for the loading mechanism operative responsive to the delivery of products thereto, means operative responsive to lowering of each rack onto the support for moving the support into position to place an empty rack in front of the loading mechanism and a loaded rack in front of the unloading mechanism, and control means for starting the unloading mechanism operative responsive to movement of the support.

7. Apparatus for handling and conveying concrete blocks from a block making machine in which the blocks are delivered on pallets from the machine comprising a conveyor for receiving the pallets from the machine and including means for supporting and moving the pallets away from the machine, a motor for driving the conveyor, control means for the motor responsive to movement of pallets from the block making machine and disposed to effect movement of the conveyor the distance occupied by a pallet, a rack on which the block carrying pallets are loaded, a

shuttle conveyor disposed to move outwardly into the rack to load it and to telescope into the stationary conveyor, a hydraulic cylinder for moving the shuttle conveyor inwardly out of the rack and control means for the hydraulic cylinder operative responsive to complete loading of the rack.

8. Apparatus according to claim 7 in which the rack is provided with a plurality of superposed shelves, a hydraulic hoist for raising the rack successively as each shelf is loaded, and control means for the hydraulic hoist operative responsive to loading the shelves.

9. Apparatus according to claim 7 in combination with a rotary support for the racks and means to rotate the support step by step responsive to complete loading and subsequent lowering of the racks.

10. Apparatus for handling and conveying concrete blocks from a block machine in which the blocks are delivered on pallets from the machine for loading onto and unloading from racks in a circular kiln, comprising a rotary support for the racks, mechanism for receiving the loaded pallets from the machine and loading them on the racks, control means for the operation of the rack loading mechanism operative responsive to delivery of pallets thereto, mechanism for lowering the racks onto the support as they are completely loaded and means to impart intermittent rotary motion to the rotary support operative responsive to lowering the racks onto the support.

11. Apparatus for handling and conveying concrete blocks from a block machine in which the blocks are delivered on pallets from the machine for loading onto and unloading from racks in a circular kiln, comprising a rotary support for the racks, mechanism for receiving the loaded pallets from the machine and loading them on the racks, control means for the operation of the rack loading mechanism operative responsive to delivery of pallets thereto, mechanism for lowering the racks onto the support as they are completely loaded, means to impart intermittent rotary motion to the rotary support operative responsive to lowering racks onto the support, a rack unloading machine disposed alongside the loading machine in position to unload the racks after they have passed around the kiln, and control means for starting the unloading machine operative responsive to movement of the rotary support.

12. Apparatus according to claim 11 in which the racks are each provided with a plurality of superposed shelves, hoists disposed under the rotary support in front of the loading and unloading machine, and control means for the hoists operative responsive to engagement with pallets on the loading and unloading machine.

13. Apparatus for handling and conveying concrete blocks from a block machine in which the blocks are delivered on pallets from the machine for loading onto and unloading from the racks in a circular kiln, comprising a rotary support in the kiln, a plurality of racks for the blocks adapted to rest on the rotary support, a machine for loading the racks disposed in front of the kiln, mechanism for lowering the racks onto the support as they are completely loaded, a hydraulic cylinder and plunger for imparting intermittent rotary motion to the support, control means for the cylinder operative responsive to the lowering of a rack onto the support, stop means for the rotary support to limit its move-

13

ment, a second hydraulic cylinder and plunger for operating the stop means, means to admit fluid under pressure to the second hydraulic cylinder from the first mentioned cylinder only after its plunger has moved a predetermined distance, and a machine for unloading the racks after they have passed around the kiln.

ROBERT M. GRAY.
